ADJUSTABLE LAND ROLLER AND HARROW

Frank M. Buschor, Celina, Ohio

Application November 11, 1943, Serial No. 509,890

1 Claim. (Cl. 55—12)

1

This invention relates to a land roller and harrow and it generally aims to provide an improved, durable and efficient construction which is adjustable according to different conditions encountered.

It is particularly aimed to provide a structure wherein a pair of rollers are provided which are adjustable so as to be selectively usable when aligned or when they are in V-relation or angularly arranged with respect to each other, in which angular position, the rollers will better aid in straight line draft and will better crush clods of dirt.

It is also aimed to provide a novel structure having harrow means both in front and in rear of the rollers, the former serving to level the ground as an aid in the rolling and crushing thereof, while the latter will impart a final harrowing action to the ground.

In addition, it is aimed to provide a novel structure having the rollers mounted in pivotally supported frames and having the adjusting means attached to both ends thereof, so that the rollers will be maintained sufficiently rigid and definitely positioned in the various positions thereof.

The more specific objects and advantages will become apparent from a consideration of the description following taken in connection with accompanying drawings illustrating an operative embodiment.

In said drawings:

Figure 1 is a plan view of the improved implement;

Figure 2 is a vertical sectional view taken on the line 2—2 of Figure 1;

Figure 3 is a vertical section taken transversely of the implement on the line 3—3 of Figure 1;

Figure 4 is an enlarged sectional view taken on the line 4—4 of Figure 3;

Figure 5 is a detail section taken on the line 5—5 of Figure 4;

Figure 6 is a vertical section taken on the line 6—6 of Figure 2;

Figure 7 is a vertical section taken on the line 7—7 of Figure 3; and

Figure 8 is a detail section taken on the line 8—8 of Figure 7.

Referring specifically to the drawings wherein like reference characters designate like or similar parts, the machine has a suitable skeletonized main frame generally designated A, the same including beams at 10 from which suitable brackets 11 suspend a rectangular or open sub-frame 12.

A pair of generally U-shaped mountings 13, 15

have central upstanding studs 14, pivotally journaled the same on longitudinally extending elements 15a of the under beams 10. Such mountings 15 have conventional land rollers 16 journaled in vertical portions 17 thereof by means of a shaft or trunnion 18. Arms 19 extend laterally from the outermost portions 17 through horizontally enlarged slots 20 of slide blocks 21 defined for movement by brackets 22 suspended from the sub-frame 12, the blocks being in direct engagement with such frame and having longitudinal grooves 22' in their lower surface which are engaged with ribs 23 of the brackets 22, to maintain the slide blocks in place.

Anchored in openings 24 of the arms 19 are cables or other flexible draw elements 25 which are guided over pulleys at 26 and 27, suitably mounted on the sub-frame 12 and which cables are similarly attached to the lower ends of levers

28, pivoted at 29 to the under beams 10, such levers 28 extending above the main frame A. It will be noted that the cables 25 extend rearwardly from the outer ends of frames. At the inner ends of such frames, links 30, by means of approximately universal joints 31, are connected to the inner vertical members 17 and extend forwardly therefrom, being attached by an approximately universal joint 32 to the lower end of the levers 33, pivoted at 34 to the under beams 10.

Levers 33 also extend above the main frame A and they pass through and above suitably shaped enlarged openings 35 in an adjusting block 36 through which an upper horizontal portion 37 of the adjusting block 36 passes, in order to slidably mount such block. The part 31 is the upper portion of a suitable bracket generally designated 38 arising from and fastened to a central beam 39 of the frame A. Such block 36 has a screw-threaded opening 40 therethrough and an adjusting screw 41 passes through such opening and meshes with the screw threads therein. Adjusting screw 41 is journaled in an upright portion 42 of the bracket 38 and held against longitudinal movement with

respect to the same as by means of collars 43. A hand wheel 44 on the screw 41 facilitates turning thereof. The forward end of the screw 41 is threaded through a cross piece 45 between the upper ends of the levers 28.

As a result of the construction described, upon turning of the screw 41, the adjusting block 36 will be moved forwardly or rearwardly according to the direction of turning which will accordingly shift the levers 33, swinging the mount-

ings 13 on their pivots 14 and angularly disposing the land rollers 16. At the same time, the screw threaded through the cross member 45, will move or enable movement of the levers 28 to follow the same to take up any slack in the cables 25 to compensate for variation in the adjustment of the rollers.

At the forward or draft end of the machine, I provide a central land roller for supporting and guiding purposes at 46. This roller has an axle or shaft 46', whereby it is journaled in a front mounting or bracket 47, having a king rod 48 journaled in the forward end of the beam 39. Also in a bearing 49 located above the beam and positioned by a bar 50 extending angularly from the beam 39. A tongue or draft means 51 is suitably connected to the mounting 47.

A driver's seat 52 is appropriately mounted as by a bar 53, on the rear end of the beam 39 and such positioned as to enable the operator while seated to turn the wheel 4 and operate the other main controls.

Forwardly of the rollers 16 and rearwardly thereof, I provide similar harrow devices B capable of being raised entirely out of engagement with the soil or lowered to any permissible depth. These harrowing devices are of skeletonized framework 54 including longitudinally extending rods 55 and longitudinally extending bars 56, parallel therewith, the framework having crossing, connecting elements 57. The bars 56 carry rigid vertical harrowing teeth or spikes while the bars or rods 55 carry in alternating relation with the latter, curved resilient spring harrow teeth 59, which preferably engage the ground at the rear of the spikes.

Rising from the framework 54 are rods 60, which are slidable through openings in the under frame 12. Such rods 60 are also slidable through a bar 61 above the main frame and they have heads 62 above bar 61. Cushioning springs 63 surround the rods 60 and are interposed between the subframe 12 and the bar 61, directly in engagement with the latter and an abutment 64 provided on rods 60. The bar 61 has crank or angle ends 65, pivotally connected at 66 to brackets 67 fastened on the main frame.

Bar 61 is also engaged by a crank 68 of adjusting levers 69, pivoted at 70 on the main frame and having latching means 71 to coact with segments 72, to secure the levers 69 at different adjustments accordingly securing the harrow means or devices B out of engagement with the ground or in engagement therewith to any desired extent, downward movement of the harrow means being urged by the springs 63, and such springs also permitting the harrow devices to yield in the event undue obstructions are encountered so as not to break or fracture.

I claim as my invention:

An implement of the class described having a frame, a mounting element pivoted on the frame, a roller journaled in the mounting element, a lever connected to the mounting element, and adjusting means operable to move the lever to vary the angle of the mounting element and roller, consisting of a block, said block having an opening engaged by the lever, means operable to slide said block comprising a screw element, a bracket on said frame mounting the screw element, a flexible connection extending from the mounting at the end opposite to said lever, a second lever to which the flexible connection is joined, and said second lever being in abutment with said screw for the purpose specified.

FRANK M. BUSCHOR.
